Primary Examiner — Richard Edgar
Assistant Examiner — Jessica Ruth Grable(57) **CLAIM**

The ornamental design for trolley for batch freeze dryer as shown and described.

DESCRIPTION

1. Trolley for batch freeze dryer

1.1 : Perspective

1.2 : Perspective

1.3 : right and left view

1.4 : Front and back view

1.5 : Top

1.6 : Bottom

1.7 : Enlarged

1.8 : Enlarged

The design shown is a trolley for entering into a freeze dryer consisting of a rack with rods and a top piece; the trolley is symmetric with respect to front/back and left/right side views.
